UNITED STATES PATENT OFFICE.

JOHN H. O'BRIEN, OF CLEVELAND, OHIO.

DESIGN FOR A STOVE.

42,176.

Specification for Design.

Patented Feb. 13, 1912.

Application filed November 4, 1911. Serial No. 658,587. Term of patent 3½ years.

To all whom it may concern:

Be it known that I, JOHN H. O'BRIEN, citizen of the United States, residing at Cleveland, in the county of Cuyahoga and State of Ohio, have invented a new, original, and ornamental Design for Stoves, of which the following is a specification, reference being had to the accompanying drawing, forming part thereof.

The figure is a perspective view of a stove, showing my new design.

I claim:

The ornamental design for a stove, as shown.

JOHN H. O'BRIEN.

Witnesses:

HARRY L. RICHEY,
W. W. LUDLOW.
